J. H. BELL,
TELEGRAPH SYSTEM.
APPLICATION FILED NOV. 24, 1915.

Patented Sept. 26, 1916.

UNITED STATES PATENT OFFICE.

JOHN H. BELL, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEGRAPH SYSTEM.

1,199,338.

Specification of Letters Patent. Patented Sept. 26, 1916.

Application filed November 24, 1915. Serial No. 63,250.

To all whom it may concern:

Be it known that I, JOHN H. BELL, a subject of the King of Great Britain, residing at East Orange, in the county of Essex and 5 State of New Jersey, have invented certain new and useful Improvements in Telegraph Systems, of which the following is a full, clear, concise, and exact description.

This invention relates to telegraph systems; more particularly to repeater systems whereby telegraphic signals may be relayed between two or more stations, and it is particularly applicable for use in telegraph systems of the so-called double current type 15 wherein the signals are composed of current impulses of opposite polarity.

Repeater systems of this general class, now in common use, are of two kinds. One employing, in a system for repeating over 20 only one telegraph line of one or more sections or what is commonly known as a single wire repeater, two pairs of polarized relays and a pair of neutral relays at each repeater station in addition to the usual keys and 25 sounders. The other employs the apparatus and circuit balances of the well-known duplex telegraph system. The first arrangement is objectionable because of the 30 number of expensive polar relays and the complexity of the necessary adjustments, while the second arrangement, in addition to requiring an excessive amount of expensive apparatus, requires the maintenance of 35 very exact resistance and capacity line balances which, being subject to weather variations, are difficult to obtain and maintain.

It is, therefore, the principal object of this invention to provide a system which is at the same time highly efficient and, because 40 of the reduction of expensive parts and difficult adjustments, cheaper and simpler than the systems now in common use.

The invention is applicable not only to single repeater systems, but is highly advantageous also for both forked and multiple repeater systems.

To these ends the invention, in accordance with its general characteristics, comprises an electromagnetically actuated device, such, 50 for example, as a polarized relay, responsive to current impulses in one section of a transmission line for controlling the application and character of current impulses imparted to another section or sections of such 55 line, together with a slow release electro-

magnetically actuated device for associating and disassociating the first mentioned device with a corresponding section or sections of the line.

The above and other objects of the invention will be fully set forth in the following description and claims, and will be more readily understood by reference to the accompanying drawing, wherein—

Figure 1 shows diagrammatically the preferred arrangement of circuits and apparatus at the terminal stations, and Figs. 2, 3 and 4 are diagrams of the connections for single, forked and multiple repeater systems respectively.

At the so-called terminal stations of the transmission lines, the character of the current impulses imparted thereto is governed by a transmitting relay 10, whose armature 11 is adapted to engage back and front contacts connected respectively to the negative and positive terminals of a source of energy, as indicated in Fig. 1. The incoming impulses from the line pass through the windings of a polarized line relay 12, whose armature 13 is connected to a grounded source of energy 14. Armature 13 coöperates with a contact connected by a conductor 15 to one terminal of a sounder 16, which may be located at the terminal station or removed to a nearby subscriber's station R, as shown in Fig. 1. Also at the subscriber's station and connected to the terminal station by a conductor 20 are a telegraph key 21 and a transmitting sounder 22 which may be of the usual well-known constructions. At the terminal station a telegraph key 23 may also be joined to conductor 20. If there is no subscriber's station, key 21 and sounders 16 and 22 may be located at the terminal 35 station, and key 23 may be dispensed with. Conductor 20 is connected to one terminal of a relay 24, the other terminal of which is joined to a terminal of relay 10, whose winding is also connected to a grounded source of energy 25. Relay 24 has an armature 26 connected to the line and coöperating with back and front contacts, respectively joined to the winding of relay 12 and armature 11 of relay 10. Relay 24 is a slow release relay, whose adjustment should be such that while its armature is readily attracted against its front contact, it is not released therefrom during the intervals between current impulses which go to make up letter or 40

100

105

110

character signal combinations of a dot and dash code, such as the Morse code. Between such combinations, however, as between words, the intervals are preferably of sufficient length to allow the armature of relay 24 to be completely retracted.

When key 21 or key 23 is depressed to start the signals, the flow of current through relays 24 and 10 cause them to attract their armatures 26 and 11 respectively. Armature 26 removes the line connection from relay 12 to armature 11, while armature 11 moves against its front contact. Current of positive potential is thereupon impressed upon the line. During the intervals between dots and dashes, armature 11 engages its back contact and negative current passes to the line, since, as hereinbefore explained, armature 26 of relay 24 does not leave its front contact during these relatively short intervals between the impulses of a letter or character combination. Relay 10, therefore, follows the manipulations of the telegraph keys, and imparts to the line positive and negative currents to represent the dots and dashes and spaces of the code employed. Relay 24, however, does not follow these manipulations, pulling up its armature on the first closure of a key and holding the armature in this condition until a key has been open a sufficient length of time to allow it to fall back. When armature 26 is against its back contact, current impulses in the line may operate the line relay 12 to control the action of the sounder 16.

Referring now to Fig. 2, the transmission line is shown in two sections, 1 and 2, leading to terminal stations or other repeater sets, and between which a repeater set arranged in accordance with this invention is located. With each section of the line there is associated a polarized relay and a slow release relay, as will be hereinafter explained. For the convenience of the repeater operator, each line section is also shown provided with a key and sounder, although this apparatus may be dispensed with if desired. Thus, line section 1 passes to a lever 30 of a key K and line section 2 passes to a lever 30 of a key K'. Levers 30 of keys K and K' coöperate with right-hand and left-hand contacts connected to opposite poles of sources of energy 32 and 33 respectively. Keys K and K' are also provided, in the usual manner, with switches 34, which normally close circuits around the key levers 30 as shown by the full lines but which, when the corresponding key is to be manipulated, may be either separately or automatically operated by key lever controlled mechanism to break the normal circuit and transfer the corresponding line section to the key lever, as shown by the dotted lines. Keys of each type are well known in the art and need no description. The relays under the control

of current impulses in line section 1 are a non-polarized relay 40 and a polarized relay 41, and the relays under the control of current impulses in line section 2 are a non-polarized relay 42 and a polarized relay 43. Relays 40 and 42 are slow release, attracting their armatures readily but not allowing them to leave their front contacts during the low magnetic intervals occurring between the dot and dash and space current intervals. The longer no-current intervals between words, however, are sufficient to cause the retraction of the armatures of relays 40 and 42.

Polarized relay 41 is provided with an armature 45 connected to a front contact co-operating with an armature 46 of relay 40 and, if desired, to a grounded polarized sounder 47. Armature 45 is located between and in its alternate positions engages right-hand and left-hand contacts, respectively connected to the positive and negative poles of source 33. In a like manner, an armature 55 of relay 43 is connected to a front contact co-operating with an armature 56 of relay 42 and a polarized sounder 57, and co-operates with right-hand and left-hand contacts connected respectively to the positive and negative poles of source 32. If it is not desired that the repeater operator hear the signals being repeated, the sounders may be dispensed with. Line section 1 is normally extended through switch 34 of key K, armature 56 and its back contact through the windings of relays 40 and 41 to ground, while line section 2 extends through switch 34 of key K', armature 46 and its back contact through the windings of relays 42 and 43 to ground. When, however, relay 40 is energized by current impulses arriving over line section 1, the path for section 2 from armature 46 through the windings of relays 42 and 43 is broken and a circuit is completed through the front contact of relay 40 to the armature of relay 41. In this condition current of a character determined by the action of polar relay 41 is impressed upon line section 2. The opening of the circuit from armature 46 through the windings of relays 42 and 43 removes what would otherwise be a path in parallel with line section 2. In a similar manner, when relay 42 is energized by current impulses arriving over line section 2, the path for section 1 from armature 56 through the windings of relays 40 and 41 is interrupted and a circuit is completed from its front contact to the armature of relay 43, so that currents controlled by the position of armature 56 are impressed upon line section 1. When, therefore, a train of positive and negative impulses comes in from a distant station over line section 1, both relays 40 and 41 are energized. Armature 46 of relay 40 associates armature 45 of relay 41 with line

section 2, so that current from source 33 flows thereover, and at the same time dis-
associates relays 42 and 43 from this section, as hereinbefore described. Subsequent posi-
5 tive and negative impulses over line section 1 cause armature 45 of relay 41 to connect the proper poles of source 33 to section 2, since, as hereinbefore explained, armature 46 of relay 40 does not become disengaged
10 from its front contact during the current reversals or low magnetic intervals occurring between the signals of a word. During the long no-current intervals between words, however, armature 46 falls back and the
15 repeater is at normal. In a like manner, signals arriving from line section 2 are repeated from source 32 to section 1, the character of such repeated impulses being determined by polarized relay 43.
20 In the forked repeater shown in Fig. 3, current impulses arriving over line section 1 operate a non-polarized slow-release relay 60 and a polarized relay 61. An armature 62 of relay 61 coöperates with contacts connected to the poles of a suitable source of energy 63 and is connected to a pair of front contacts associated with armatures 64 and 65 of relay 60. In a similar manner, line section 2 is associated with a non-polarized slow-release relay 70 having a pair of armatures 74 and 75, and with a polarized relay 71 having an armature 72 controlling the application of current from a source of energy 73; and line section 3 is associated
25 with a non-polarized slow-release relay 80 equipped with armatures 84 and 85, and with a polarized relay 81 provided with an armature 82 controlling the application of current from a source of energy 83.
30 When signal current impulses arrive over line section 1, they pass, by way of armature 84 and the coöperating back contact of relay 80, and armature 74 and the coöperating back contact of relay 70, through relays 60 and 61. The first impulse of a combination causes both relays 60 and 61 to operate, relay 60 connecting armature 62 to line section 2 through armatures 65 and 85, and to line section 3 through armatures
35 64 and 75, while relay 61 causes its armature 62 to connect with the proper pole of source 63. Relay 61 follows the subsequent im-
40 pulses of the combination, so that the currents over section 1 are relayed to sections 2 and 3 from source 63, since relay 60 does not allow its armatures to disengage their front contacts until during the comparatively long intervals between words. In like manner, impulses arriving over line section 2
45 are relayed to line sections 1 and 3 from source 73 through the agency of relays 70 and 71, and impulses arriving over line section 3 are relayed to line sections 1 and 2 from source 83 through the agency of relays 80 and 81. To avoid confusion, no re-

peater operators' keys or sounders are shown in connection with this circuit, but such apparatus may be added, when desired, in exactly the same manner as shown in Fig. 2.

In the multiple repeater, to avoid a multiplicity of contacts on the non-polarized slow release relays, two extra relays for each line section are employed. Thus, referring to Fig. 4, it will be noted that line section 1 is associated with a non-polarized slow-release relay 90 and a polarized relay 91, as in the single and forked repeaters. In addition, there is a current control or transmitting relay 92 and a slow release line or section control relay 93. Slow release relay 90 is provided with a pair of armatures 94 and 95, and polarized relay 91 is provided with an armature 96 coöperating with a contact connected to a grounded source of energy 97. Relay 92 is provided with an armature 98 coöperating with back and front contacts connected respectively to the negative and positive poles of a suitable source of energy, as shown, while relay 93 is provided with an armature 99 connected to line section 1 and coöperating with a front contact connected to armature 98 and a back contact connected to a circuit through the windings of relays 90 and 91. The other line sections are associated with relays in a similar manner. For section 2 there is a neutral slow-release relay 100 provided with armatures 101 and 102, a polarized relay 103 having an armature 104 adapted to coöperate with a source of energy 105, a transmitting relay 106 having an armature 107, and a line control relay 108 provided with an armature 109.

A sufficient understanding of the multiple repeater system may be obtained from a description of its operation, which is as follows: Assuming that a character combination of impulses is arriving over line section 1, the first such impulse will pass through armature 99 and the windings of relays 90 and 91. Relay 90 attracts its armatures 94 and 95, armature 94 preparing a circuit from armature 96 through the front contact and armature 94 of relay 90, armature 102 and back contact of relay 100, winding of relays 106 and 108, back contact and armature 101 of relay 100, armature 110 and back contact of a neutral slow-release relay 111, the windings of a relay 112 and a neutral slow-release relay 113, back contact and armature 114 of relay 111, armature 120 and back contact of a neutral slow-release relay 121, windings of a relay 122 and a neutral slow-release relay 123, back contact and armature 124 of relay 121, armature 130 and back contact of a neutral slow-release relay 131 and the windings of a relay 132, and a neutral slow-release relay 133 through the back contact and armature 134 of relay 131 to armature 95 of relay 90.

This circuit is grounded at one end through the front contact coöperating with armature 95, and at the other end through grounded source of energy 97 by armature 96. Current flows in this circuit and relays 106, 108, 112, 113, 122, 123, 132 and 133 pull up their armatures. The armatures of relays 108, 113, 123 and 133 respectively connect line sections 2, 3, 4 and 5 with armatures 107, 135, 136 and 137 of transmitting relays 106, 112, 122 and 132, and since these relays are also energized, as hereinbefore explained, a positive current flows over line sections 2, 3, 4 and 5. This current flows until a reversal in line section 1 causes armature 96 of relay 91 to become disengaged from association with source 97, whereupon relays 106, 112, 122 and 132 are deenergized and their armatures fall back, causing negative current to pass over their respective sections, since, as in the case of the single and forked repeaters, the slow-release relays 90, 108, 113, 123 and 133 do not allow their armatures to leave their coöperating front contacts during the low magnetic intervals during current reversals or the intervals between the impulses making up a word. Subsequent impulses arriving over line section 1 are followed by armature 96 of relay 91, which, by opening and closing the hereinbefore traced circuit through transmitting relays 106, 112, 122 and 132, causes currents of the proper duration and polarity to be impressed upon line sections 2, 3, 4 and 5. During the longer intervals between words, however, slow-release relays 90, 108, 113, 123 and 132 allow their armatures to fall back and the repeater is again at normal.

In a similar manner, impulses arriving over line section 2 are repeated over line sections 1, 3, 4 and 5, the circuit through the various relays being grounded through the front contact of armature 102 and connected to source 105 at the proper times by armature 104 of polarized relay 103. The same is true of impulses arriving over line section 3, which are repeated to line sections 1, 2, 4. Although several sources of current have, for convenience, been shown in the drawing it will be understood that each one of the correspondingly poled sources may be and preferably are one and the same current source.

The invention claimed is:

1. In a telegraph repeating system, sources of current therefor, a plurality of line relay groups, a telegraph line circuit for each group, and contacts operated by the relays of any group to include said sources of current to repeat telegraphic signals into the line circuits of the other relay groups.

2. A telegraph system comprising a transmission line divided into a plurality of sec-

tions, an electromagnetically-actuated device associated with each said section and controlling the character of signal current impulses imparted to other of said sections, and a slow release electromagnetically-actuated device for each said section acting when in operation to associate another said section with a corresponding one of said first mentioned devices and disassociate the other said section and the other said slow release device.

3. A telegraph system comprising a transmission line divided into sections, a polarized relay adapted to be associated with each of said sections and controlled by current impulses traversing a corresponding section to control the character of current impulses in another section, and a non-polarized slow-release relay for each said section acting to associate the polarized relay of a corresponding section with another said section and to disassociate other said polarized and slow-release relays from their corresponding sections.

4. A telegraph system comprising a transmission line divided into sections, a polarized relay adapted to be associated with each of said sections and controlled by current impulses therein to determine the character of current impulses in other sections, and a slow-release relay for each said section acting to associate the polarized relay of a corresponding section with other sections and to disassociate other said polarized and slow-release relays from their corresponding sections.

5. In a telegraph repeating system, a plurality of line relay groups, a telegraph line circuit for each group, and contacts operated by a relay in any one of the groups to disable the relays of the other groups.

6. In a telegraph repeating system, a plurality of line relay groups, a telegraph line circuit for each group, and contacts operated by a relay in any group to join the line circuits of the other groups one with another.

7. In a telegraph repeating system, sources of current therefor, a plurality of line relay groups, each comprising a slow release relay and a polarized relay, a telegraph line circuit for each group, contacts operated by the slow release relay of any group when active to disable the relays of the other groups and to join the line circuits of the other relay groups one with another, and contacts operated by the polarized relay of the active group for including said sources of current to repeat telegraphic signals into the joined line circuits.

In witness whereof I hereunto subscribe my name this 20th day of November, A. D. 1915.

JOHN H. BELL
